(57) **CLAIM**

The ornamental design for a pet relief station, as shown and described.

DESCRIPTION

FIG. 1 is a perspective view of the pet relief station showing the design with interior shelves in condition of use.

FIG. 2 is a front elevational view of the pet relief station shown in FIG. 1.

FIG. 3 is a rear elevational view of the pet relief station shown in FIG. 1.

FIG. 4 is a left side elevational view of the pet relief station shown in FIG. 1.

FIG. 5 is a right side elevational view of the pet relief station shown in FIG. 1.

FIG. 6 is a top plan view of the pet relief station shown in FIG. 1.

FIG. 7 is bottom plan view of the pet relief station shown in FIG. 1.

FIG. 8 is a perspective view of the pet relief station showing the interior shelves in folded position.

FIG. 9 is a front elevational view of the pet relief station shown in FIG. 8.

FIG. 10 is a rear elevational view of the pet relief station shown in FIG. 8.

FIG. 11 is a left side elevational view of the pet relief station shown in FIG. 8.

FIG. 12 is a right side elevational view of the pet relief station shown in FIG. 8.

FIG. 13 is a top plan view of the pet relief station shown in FIG. 8.

FIG. 14 is bottom plan view of the pet relief station shown in FIG. 8.

FIG. 15 is a perspective view of the pet relief station in a closed position.

FIG. 16 is a front elevational view of the pet relief station shown in FIG. 15.

FIG. 17 is a rear elevational view of the pet relief station shown in FIG. 15.

(Continued)

FIG. 18 is a left side elevational view of the pet relief station shown in FIG. 15.

FIG. 19 is a right side elevational view of the pet relief station shown in FIG. 15.

FIG. 20 is a top plan view of the pet relief station shown in FIG. 15; and,

FIG. 21 is bottom plan view of the pet relief station shown in FIG. 15.
